UNITED STATES PATENT OFFICE.

GEORGE W. MCGILL, OF NEW YORK, N. Y.

DESIGN FOR A METALLIC FASTENER.

SPECIFICATION forming part of Design No. 22,823, dated October 3, 1893.

Application filed September 9, 1893. Serial No. 485,195. Term of patent 14 years.

To all whom it may concern:

Be it known that I, GEORGE W. MCGILL, a citizen of the United States, residing at Riverdale, New York, in the county of New York, 5 State of New York, have invented and produced a new and original Design for Metallic Fasteners, of which the following is a specification.

This design has for its object to provide a 10 novel and ornamental decorative metallic fastener, and consists in a fastener having a star shaped head, fashioned on its upper surface in relief, and extending from its under surface two superimposed prongs.

15 The design is illustrated by the accompanying drawings, in which—

Figure 1 is a perspective view of the fastener showing its embossed upper surface and part of its superimposed prongs, and Fig. 20 2 represents the under or pronged surface of the fastener.

In the drawings the numeral 1 indicates the

star shaped head having its upper surface struck in relief and the numeral 2 indicates the under surface from the center of which extend the two superimposed prongs 3 and 4.

The design provides a novel and ornamental decorative metallic fastener which presents a striking and characteristic appearance.

30 What I claim is—

The design for a decorative metallic fastener having a star-shaped head fashioned on its upper surface in relief and extending from its under surface two superimposed prongs, 35 substantially as shown and described.

In testimony whereof I have hereunto set my hand and affixed my seal in the presence of two subscribing witnesses.

GEORGE W. MCGILL. [L. S.]
